WALTER H. SCHRAMM, OF PITTSBURGH, PENNSYLVANIA, ASSIGNOR TO WESTINGHOUSE ELECTRIC & MANUFACTURING COMPANY, A CORPORATION OF PENNSYLVANIA

INSTRUMENT TEST SWITCH

Application filed November 6, 1928. Serial No. 317,647.

My invention relates to test switches and particularly to switches for controlling current-measuring instruments and the like.

An object of my invention is to provide a test switch that may be mounted upon a switchboard panel and is operable from the front of the switchboard and wherein no live parts are exposed at the front of the switchboard.

Another object of my invention is to provide a test switch that is operable from the front of the switchboard and wherein all test connections are carried by a test plug that is removably inserted in the test switch when it is desired to make a test of the instrument controlled by the switch.

Another object of my invention is to provide a test switch having the above-noted characteristics wherein the current-controlling switch is permanently mounted in an enclosing unit; wherein the test plug is provided with test contacts that engage contacts in the enclosing unit for connecting a test meter in the instrument circuit and wherein the plug is provided with means for actuating the switch to open position after the test contacts have engaged the contacts within the enclosing unit and have established a circuit through the test connections.

A further object of my invention is to provide an instrument test switch wherein improper operations are precluded and wherein a test plug is provided that cannot be removed from the switch without first restoring it to its normal operative position.

Another object of my invention is to provide a test plug for a test switch wherein the test contacts are mounted upon conductor straps extending through the handle of the test plug, the straps being of such construction that desired connections may be made by joining certain of the straps at the ends remote from the contacts and wherein the said ends of the conductor straps may be exposed for alterations in their connections by displacing a portion of the test-plug handle.

A further object of my invention is to provide an instrument test switch that shall be compact and inexpensive to manufacture and may readily be mounted upon a switch-

board panel in such manner that it is available for operation from the front of the switchboard panel.

These and other objects that will be made apparent throughout the further description of my invention are attained by means of the test-switch apparatus hereinafter described, and illustrated in the accompanying drawings, wherein;

Figure 1 is a longitudinal sectional view through a test-switch unit embodying features of my invention.

Fig. 2 is a longitudinal section through a test plug for cooperating with the test-switch unit shown in Fig. 1.

Fig. 3 is an end view of the test switch shown in Fig. 1.

Fig. 4 is a longitudinal sectional view, taken on the line IV—IV of Fig. 1.

Fig. 5 is a transverse sectional view, taken on the line V—V of Fig. 1.

Fig. 6 is a transverse sectional view, taken on the line VI—VI of Fig. 1.

Fig. 7 is a transverse sectional view, taken on the line VII—VII of Fig. 1.

Figs. 8 and 9 are front and end elevational views, respectively, of the rear end plate of the test-switch enclosure.

Fig. 10 is a longitudinal section through the end plate shown in Fig. 8, taken on the line X—X thereof, and

Fig. 11 is a perspective view of the switch assembly of the test-switch unit.

Referring to the drawings, and particularly to Figs. 1, 4 and 5, the test-switch unit comprises a pair of insulating end plates 12 and 13 that are retained in spaced assembled relation by means of four identical and, therefore, interchangeable contact strips 14, 15, 16 and 17 that are provided with laterally bent ends to engage the end plates. The ends which engage the plate 12 are secured thereto by screws 18 and those which engage the plate 13 are secured thereto by terminal screws 19.

The contact strips 14, 15, 16 and 17 are severally provided with two laterally extending wings 21 that are of such length and are so spaced apart, as indicated in Fig. 4, that the integral contact jaws with which they are provided are in two side-by-side planes. The

contact strips 14 and 17 carry contact jaws 22 and 23 and the contact strips 15 and 16 carry contact jaws 24 and 25. The contact jaws are thus disposed in two opposite rows having four pairs of contact jaws 22, 24, 23 and 25 that are adapted to receive bridging switch blades to be hereinafter described.

As indicated, in Fig. 7, the test switch is of the double-pole type and when a bridging switch blade, to be hereinafter described, connects the contacts 22 or the contacts 23, a current path from one pole of a circuit is established through contact strips 14 and 17 and the conductor terminals 26 and 27 that are respectively connected thereto.

When the bridging switch blades connect the contact jaws 24 and 25, current path is established from the other pole of the circuit through the contact plates 15 and 16 that are connected, respectively, to conductor terminals 28 and 29.

In order to establish connections between the contact jaws 22 and between the contact jaws 24, a rotary-switch assembly 31 is provided which comprises a substantially square insulating block 32 having its diagonal corners rounded, as indicated in Figs. 6, 7 and 11, and is provided with a cylindrical journal shaft 33 of reduced diameter which is adapted to fit within a circular bearing 34 provided centrally in the end plate 13. The block 32 is provided with a pair of switch blades 35 and 36 that are aligned with the contact jaws 22 and 24, respectively, and which engage them when the switch block 32 is in the extreme closed position shown in Figs. 1 and 7.

The end plate 13 is provided with a pair of stop members 37 and 38 that are adapted to be engaged by the square corners 39 and 41 of the block 32 when the switch is moved to the closed position shown in Figs. 1 and 7, and to limit opening movement of the switch block by engaging the corners after it has been rotated, through 90°, to open position, the square corners 39 and 41 then engaging the stop lugs 38 and 37, respectively. It will be seen, therefore, that rotation of the switch block 32 in a counter-clockwise direction through 90° moves the switch blades 35 and 36 to full-open position.

In order to connect a test instrument in the instrument circuit controlled by the switch, it is desirable to establish the instrument circuit through the test circuit before the switch blades 35 and 36 are moved to open position.

It is apparent from the foregoing that, if bridging switch blades are inserted between the contact jaws 23 and between the contact jaws 25, a circuit will be maintained through the instruments connected to the switch after the switch blades have been moved to open position.

The test plug for connecting a test instrument in the circuit is illustrated in Fig. 2 and comprises an insulating tube 42 having

an enlarged insulating handle 43 that may be detached therefrom when desired. Within the tube 42, four conductor straps 44, 45, 46 and 47 are mounted, the straps being insulated from one another by means of insulation 48 and retained in assembled relation by means of rivets 49.

As indicated in Fig. 2, the outermost straps 44 are provided with radially extending contact blades 51 and 52, respectively, the latter being of greater length than the former, for reasons that will hereinafter appear. The innermost straps 45 and 46 are respectively provided with radially extending contact blades 53 and 54, the blade 54 being longer than the blade 53 and the distance between the blades 52 and 54 being the same as the distance between the centers of the contact jaws 23 and 25 of the test switch in order that the blades of the test plug may register with the contact jaws 23 and 25 when the plug is inserted within the test switch.

As indicated in Fig. 2, the conductor strap 48 is connected to a conductor 55, and the conductor strap 47 is connected to a conductor 56, and the conductor straps 45 and 46 are connected, at their ends, to each other by means of a rivet 57. Accordingly the blades 53 and 54 constitute a bridging switch blade for connecting the contact jaws 23, and the blades 51 and 52 are connected to one another through the test instrument (not shown) that is connected between the conductors 55 and 56.

It will be understood that other test arrangements and connections may be made by means of the plug by changing the connections of the conductors 55 and 56 with the conductor straps and by connecting different straps to each other. For instance, the blades 54 and 52 may be made to constitute a bridging switch for a pair of the contact jaws 23 and 25, in which event, the ends of the conductor straps 47 and 46 will be riveted together, and the conductor 56 will be connected to the conductor strap 45. A variety of test connections may be made by simply changing the connections at the rear end of the test plug.

The test-switch unit is mounted upon a switchboard panel 57a having an opening 58 therein of the keyhole type. A front plate 59, made of insulating material and having a keyhole slot 61 registering with the opening 58 in the panel, is secured to the panel by means of screws 62 that extend through the panel and are threaded into threaded sockets 63 in the end plate 12, which is also provided with a keyhole slot 64 that is aligned with the opening 58 in the panel 57.

By reference to Fig. 3, it will be seen that the keyhole slot 61 in the front plate 59 comprises a circular central portion and two relatively narrow end portions 65 and 66,

the latter being longer than the former for permitting the insertion of the long contact blades 52 and 54 of the plug, thus insuring that the plug will be inserted in but one position, thereby rendering it impossible to so insert the plug that improper circuit connections will be made.

The inner end of the switch block 32 (Figs. 1 and 11) is provided with a transverse notch 67, the walls of which diverge from a central point to its outer extremities and the narrow central portion of which is slightly larger than the width of the contact blades 53 and 54 of the test plug so that the notch will receive them when the plug is inserted in the test-switch housing through the keyhole slot 61.

The notch 67 is so shaped that it permits a limited degree of rotating movement of the test plug relative to the block, for a purpose to be hereinafter described.

During the normal operation of the switch, the bridging switch blades 35 and 36 are disposed in the closed positions shown in Figs. 1 and 7. When it is desired to test the instrument associated with the switch, the test plug is inserted until the contact blades 53 and 54 enter the notch 67 in the end of the switch block 32. At this time, the blades 53 and 54 align with the contact jaws 23, and the blades 51 and 52 align with the contact jaws 25. The block is then rotated in a counter-clockwise direction, as indicated by the arrow in Fig. 3.

Initial rotation of the plug does not impart movement to the switch block 32, because of the lost-motion connection therewith, until the blades 51, 52 and 53 and 54 have entered the switch jaws 25 and 23, respectively, thus establishing a connection through the test instrument before causing disengagement of the switch blades 35 and 36 from the contact jaws 22 and 24.

After the blades 35 and 36 have been disengaged from their respective contacts, current flows through the conductors of the test plug and through the test instrument without causing interruption of the circuit through the instrument being tested.

Since the contact blades 51 to 54 of the test switch are, at this time, between the contact jaws 23 and 25, the test plug cannot be withdrawn longitudinally. In order to withdraw the test plug, it is first necessary to rotate it through substantially 90° in order to bring the contact blades 51, 52, 53 and 54 into alignment with the transversely disposed keyhole slot 61. This operation first returns the switch block to its closed position, insuring reestablishment of the original circuit.

The end plate 12 is provided with four lugs 68, 69, 70 and 71, the latter two being of greater length than the former two and extending across the path of movement of the blades 51 and 52 of the test plug to constitute

stops for limiting the rotary movement of the plug. The four lugs also serve to prevent any rotary movement of the plug until it has been moved to its operative position wherein the contact blades 51 to 54 accurately align with the contact jaws 25 and 23.

Referring to Figs. 1, 9 and 10, it will be noted that the end corners of the lugs 68 and 69 are rounded at 72 in order to cam the test lug into its extreme inner position in the event that it is rotated slightly before the plug has reached its innermost position.

By reason of the construction herein disclosed, instrument tests are greatly facilitated, and it is not necessary to connect wires to the switch through the medium of test connections exposed at the front of the switchboard panel, as has been the present practice.

In the usual switchboard installation, a large number of instruments are arranged in a horizontal row along the switchboard and, by reason of this construction, the operator may move along the switchboard and rapidly insert the test plug and take readings on the successive instruments in a very short time. The arrangement is such that, where necessary, simultaneous tests of instruments may be made when conditions so require, by arranging a plurality of test plugs within the test switches and connecting the test plugs with a mechanical driving connection for simultaneously rotating the plugs.

While I have illustrated only one embodiment of my invention, it will be apparent to those skilled in the art that various changes, modifications, substitutions, additions and omissions may be made in the apparatus illustrated without departing from the spirit and scope of my invention as set forth in the appended claims.

I claim as my invention:

1. The combination with a test switch having a plurality of contacts and a movable switch member for engaging certain of the said contacts, of a rotatable test plug having means for operatively engaging the movable switch member when moved in an axial direction and having switch members for engaging other of the said contacts when rotated for moving the switch member.

2. The combination with a test switch having a plurality of contacts and a rotatable switch member for engaging certain of the said contacts, of a rotatable test plug having means for operatively engaging the movable switch member when moved in an axial direction and having switch members so disposed that they engage other contacts when rotated for moving the switch member and before the latter is moved out of engagement with its respective contacts.

3. Test-switch mechanism comprising a support, a plurality of contacts on the support, a rotatable contact mounted on the support and movable into engagement with certain

of the contacts, and a rotatable test plug for operatively engaging the movable contact when moved in an axial direction and whereby rotary movement of the plug imparts rotary movement to the movable contact, and a contact on the plug for engaging the other contacts when rotated for moving the rotatable contact.

4. Test-switch mechanism comprising a support, a plurality of contacts on the support, a contact mounted on the support and rotatable into engagement with certain of the contacts, and a rotatable test plug for operatively engaging the movable contact when moved in an axial direction and whereby rotary movement of the plug imparts rotary movement to the rotatable contact, and a contact on the plug for engaging the other contacts when rotated for moving the rotatable contacts and before the latter is disengaged from its respective contacts.

5. Test-switch mechanism comprising a support, a plurality of contacts on the support, a rotatable switch mounted on the support for engaging certain of the said contacts, a rotatable test plug having contacts for engaging other of said contacts adapted to be inserted in the support by a longitudinal movement of the plug and provided with means for engaging the rotatable switch whereby the switch is rotated with the plug, the said contacts of the plug being so disposed that they engage their respective contacts only when rotated and before the switch is disengaged from its respective contacts.

6. A test switch comprising a pair of end members, a pair of contact plates for connecting the end members and retaining them in assembled position, contacts mounted upon the said plates, a movable switch mounted on one of the members for engaging certain of the said contacts, and a test plug removably supported by the other member for engaging and operating the switch member and having a contact thereon for engaging other of the said contacts.

7. A switch comprising a pair of end members, four interchangeable contact plates for joining the end members and for retaining them in spaced relation, the said plates having contacts so disposed that they are aligned in two separate rows between the said end members, and a switch carried by an end member having contacts for engaging a contact of each row.

8. A test switch comprising a support, a plurality of contacts mounted on the support, a rotatable switch mounted on the support for engaging certain of the said contacts, a removable test plug mounted upon the support for longitudinal and rotary movement and movable longitudinally into operating engagement with the switch, and rotatably movable into engagement with the other of the said contacts, the said contacts on the plug

preventing longitudinal disengaging movement of the plug so long as they are in engagement with the said other contacts.

9. A test switch comprising a support, a plurality of contacts mounted on the support, a rotatable switch mounted on the support for engaging certain of the said contacts, a removable test plug mounted upon the support for longitudinal and rotary movement and movable longitudinally into operating engagement with the switch, and rotatably movable into engagement with the other of the said contacts only when in operative relation to the switch.

10. A test switch comprising a pair of end members, a pair of contact plates for connecting the end members and retaining them in assembled position, contacts mounted upon the said plates, a movable switch mounted on one of the members for engaging certain of the said contacts, a test plug movably supported by the other member for engaging and operating the switch member and having a contact thereon for engaging other of the said contacts, and means on the end members for limiting rotary movement of the switch and the plug.

In testimony whereof, I have hereunto subscribed my name this 26th day of October, 1928.

WALTER H. SCHRAMM.
